Watson E. Coleman
ATTORNEY.

UNITED STATES PATENT OFFICE.

BESSIE MAE BODDY, OF MARCELINE, MISSOURI.

COMBINED LID AND WASHDRAIN FOR WASHBOILERS.

Application filed February 23, 1921. Serial No. 447,267.

To all whom it may concern:

Be it known that BESSIE MAE BODDY, citizen of the United States, residing at Marceline, in the county of Linn and State 5 of Missouri, has invented certain new and useful Improvements in Combined Lids and Washdrains for Washboilers, of which the following is a specification, reference being had to the accompanying drawings.

10 This invention relates to combined lid and wash drain for wash boilers, and has for its object to provide a device of this character which may be adapted for use in connection with a conventional form of 15 boiler to provide a lid.

Another object is to provide a device of this character wherein the lid when inverted serves as a drain receptacle for the clothes after they are removed from the boiler.

20 A further object of the invention is to provide a device of this character having an intermediate dished portion adapted when the lid is inverted to receive the clothes, and to also serve as a steam dome when the lid is 25 maintained in its natural position.

A still further object of the invention is to provide a device of this character wherein the dished intermediate portion of the lid serves to properly support the lid when it 30 is used for draining clothes.

A still further object is to provide a device of this character having novel means for draining the same when in its inverted position.

35 With these and other objects in view the invention consists in the improved construction and arrangement of parts to be herein-after more particularly described and claimed.

40 Figure 1 is a perspective view of a wash boiler showing the lid applied.

Figure 2 is a transverse sectional view of the boiler showing the position of the lid when used as a clothes drain,

45 Figure 3 is a side elevation of the lid,

Figure 4 is a top plan view,

Figure 5 is a transverse sectional view, and

Figure 6 is an end elevation.

50 Referring to the drawings, A designates a conventional form of boiler such as used for washing clothes, the boiler having the usual reinforcing bead B.

A lid 5 is provided for use in connection 55 with the boiler, said lid comprising a sheet of material 6 having its intermediate por-

tion 7 curved longitudinally of the sheet. The ends 8 and 9 are extended in angular relation to the intermediate portion 7 and are disposed substantially in the same plane 60 and disposed parallel with the upper edge of the boiler A. By this arrangement, the ends 8 and 9 provide substantial supports when the device is being used as a lid. It will be noted that the intermediate portion 65 7 is relatively long and that the curvature thereof is gradual so that a long and rather deep dome is provided. The dome is completed by side members 10 and 11. Each of said side members having one of their 70 longitudinal edges curved from end to end so as to conform to the contour of the intermediate portion 7.

The ends 8 and 9 are each provided with an arcuate flange 12 which depends from the 75 lower surface of said ends inwardly of their edges so that these flanges will engage the inner surface of bead B of the boiler at the end of the boiler to maintain the lid in its proper position. As shown in Figure 2 the 80 flanges 12 coact with the end portions 8 and 9 to provide spaced individual trays. To assist in retaining the lid in engagement with the boiler each side member 10 and 11 is provided with a reinforcing strip 13, said 85 strip being secured to the inner side of said side member and adapted to depend below the edge thereof to serve as a retaining flange capable of cooperating with the flanges 12, said flanges being adapted to engage the inner surface of the base B. Extending longitudinally of the outer surface of the lid in parallel relation to each other, is a pair of braces 14 which extend to the 90 end portions 8 and 9 and are adapted to 95 brace the intermediate portion 7. Handles 15 are secured to the upper surface of the end portions 8 and 9 and are supported by said braces.

Each of the sides 10 and 11 has the intermediate portion of its curved longitudinal edge provided with a series of perforations 16. Carried by the upper surface of each of said sides, is a pair of guide members 17 which extend above and below the perforations. These guide members are adapted to slidably support a sliding valve 18 provided with an operating knob 19, by means of which the perforations are closed and opened.

When the lid is in the position as shown in Figure 1, the intermediate portion 7

serves as a steam dome to permit steam generated within the boiler to accumulate therein. In view of the curvature of said dome the steam will be directed to the center 5 thereof, where it will be permitted to escape when desired by operating the valves 18 so that there is no danger of the steam forcing the lid from the boiler in order to escape. After the clothes have been boiled, 10 the lid 5 is removed and inverted and positioned transversely of the boiler as shown in Figure 2. The lid then serves as a receptacle capable of receiving clothes previously deposited in the boiler. When in this position the valves 18 may be opened so as to permit water removed with the clothes to pass through the perforations 16 back into the boiler. The individual trays provided by inverting the cover are intended to receive 15 clothes that have been drained, if it is not convenient to move the boiler so as to convey the clothes to another place, thereby leaving the intermediate portion of the cover for the reception of other clothes to be drained. 20 It will be noted that the intermediate portion of the dome extends inwardly of the boiler so as to prevent the lid from being accidentally disengaged from the bead B when in its inverted position. It will also 25 be noted that the flanges 12 and 13 serve to increase the depth of the receptacle so that a large number of clothes may be deposited for draining.

From the foregoing it will be readily seen that this invention provides a novel device 35 which not only serves as a lid but as a drain capable of being readily positioned for use without requiring any special fastening means or strips.

What is claimed is:

1. A wash boiler cover clothes drain consisting of a sheet of metal having its central portion curved longitudinally and having its end portions extended outwardly substantially in the same plane, side members carried by the longitudinal edges of the curved portion of the sheet, said side members terminating at the junction of the end portions with the curved portion of the sheet. 45

2. A wash boiler cover clothes drain comprising a sheet of metal having its intermediate portion curved longitudinally, said curved portion terminating inwardly of the ends of the sheet, the end portions being flat and extended outwardly in angular relation to the curved portion of the sheet, side members for the sides of said curved portion, each side member having one longitudinal edge curved and connected to one of the longitudinal edges of said curved portion, the opposite longitudinal edge of each side member terminating in the plane of the lower face of said end portions. 55

In testimony whereof I hereunto affix my signature.

BESSIE MAE BODDY.
